UNITED STATES PATENT OFFICE

160,048

FACSIMILE TRANSMITTER

Raleigh J. Wise, Arlington, Robert D. Parrott, West New York, and Garvice H. Ridings, Summit, N. J.

Application January 4, 1950, Serial No. 6,992

Term of patent 14 years

(Cl. D26—5)

To all whom it may concern:

Be it known that we, Raleigh J. Wise, Robert D. Parrott, and Garvice H. Ridings, citizens of the United States, residing at Arlington, West New York, and Summit, respectively, counties of Hudson, Hudson, and Union, respectively, State of New Jersey, have invented a new, original, and ornamental Design for a Facsimile Transmitter, of which the following is a specification, reference being had to the accompanying drawing, forming part thereof.

In the drawings, Fig. 1 is a perspective view of a facsimile transmitter, showing our new design; and

Fig. 2 shows a plan view of the transmitter on a larger scale.

We claim:

The ornamental design for a facsimile transmitter, as shown.

RALEIGH J. WISE.
ROBERT D. PARROTT.
GARVICE H. RIDINGS.
